COLLAPSIBLE CABINET

Harry Derman, Laurelton, N. Y.

Application February 24, 1941, Serial No. 380,118

8 Claims. (Cl. 312—144)

This invention relates to collapsible cabinets particularly of the type employing corrugated or fiber board walls with wood strip reinforcements, and the object of the invention is to provide a cabinet of the character described employing a door frame unit comprising a rigid wood frame defining a door opening and doors movably mounted in said frame for controlling said opening, a further object being to provide means for pivotally mounting the swing doors in a frame without the use of hinges, a still further object being to provide cooperating means between the doors and frame for supporting the doors in closed position, and with these and other objects in view, the invention consists in a cabinet of the class and for the purpose specified, which is simple in construction, efficient in use, and which is constructed as hereinafter described.

The invention is fully disclosed in the following specification of which the accompanying drawing forms a part, in which the several parts of my invention are designated by suitable reference characters in each of the views, and in which:

Fig. 1 is a perspective view of a cabinet showing one form of the improved construction.

Fig. 2 is a partial section on the broken line 2—2 of Fig. 1.

Fig. 3 is a partial section on the line 3—3 of Fig. 1 on an enlarged scale.

Fig. 4 is an enlarged section on the line 4—4 of Fig. 2.

Fig. 5 is a view similar to Fig. 2 showing a modification.

Fig. 6 is a partial section on the line 6—6 of Fig. 5.

In producing collapsible cabinets, and particularly cabinets of the inexpensive type constructed of corrugated or fiber board and wood reinforcing strips or rails, it has been the custom when swinging doors are desired to employ hinges of a more or less conventional type. When hinges are employed, however, it is necessary to use two or three hinges on each door, thereby adding materially to the cost of the cabinet not only because of the initial cost of the hinges, but also because of the labor involved in positioning and mounting these hinges. Furthermore, the small inexpensive hinges normally used in cabinets of the class under consideration, provide a very light door mounting which is loose-jointed, noisy and generally impractical. It is the object of the present invention to provide a new type of swinging door mounting which not only is simple and inexpensive in construction, but which also in-

sures sturdy support and smooth operation of the doors while at the same time improving the appearance of the cabinet.

To illustrate one adaptation of my invention, I have shown in Figs. 1 to 3 of the drawing, a cabinet 10 comprising a unitary member 11 forming side and rear walls of the cabinet, top and bottom walls 12 detachable with respect to the member 11, and a front door frame unit 13. The frame 13 includes transverse rails 14 grooved to engage flanges 12a on the top and bottom walls, and vertical rails 15 grooved to engage flanges or front panels 11a of the member 11. The rails 15 are preferably interlocked with the rails 14 as seen in Figs. 2 and 3 of the drawing at points inwardly of the ends of the rails 14, and may be secured together by suitable cement or attaching devices. The door frame unit 13 further includes a pair of swinging doors 16—16a supported in the frame as a permanent part thereof. It will thus be apparent, that the complete cabinet comprises essentially four detachably related parts which may be quickly and readily assembled and joined together in the usual manner by suitable fastening devices in setting up the cabinet for use.

Each of the doors 16—16a comprises a panel 17 of corrugated board or the like, along vertical edges of which are arranged reinforcing wood strips of simple L-shaped contour as seen at 18, or of irregular contour as seen at 19—19a. The irregular contours in the strips 19—19a provide an interfitting relation between abutting edges of the doors when in closed position. It will of course be apparent however, that in some forms of construction the simple type of reinforcing strip 18 may be employed along both vertical edges of each door. In the form of construction shown in Figs. 1 to 4, the transverse wood strip 20 is employed along upper and lower edges of each door and interfitting with the vertical strips as seen at 21 in Fig. 4, thereby producing a rigid and strong door construction which at the same time is neat and attractive in appearance.

The doors 16—16a are pivotally mounted at remote edges thereof in the frame 13 by means of dowel pins 22 (note particularly the lower end of Fig. 2) registering with recesses 23 in the transverse rails 14, and corresponding recesses 24 in the ends of the vertical strips 18.

The recesses 23 and 24 are drilled before the frame 13 is assembled, and the dowel or pivot pins 22 are arranged in one of each pair of the registering recesses 23, 24. The various pins are then inserted in the other of said recesses while at the

same time the transverse rails 14 are moved toward each other until the desired closeness of fit of the doors is obtained. The transverse rails are then positively secured to the vertical rails as previously described, thereby completing the main assemblage of the unit 13. To complete the unit 13, a stop strip 25 is secured along inner surfaces of the top and bottom transverse rails 14 in a manner to extend into the door opening as seen in Fig. 2 of the drawing, and to register with inner surfaces of the vertical door strips 19-19a (note Fig. 3). Centrally of the upper transverse rail and in the surface thereof, bounding the door opening, is secured a spring catch member 26 which cooperates with a projecting knob or pin 27 on the vertical door strip 19. When the door is in the fully closed position the knob 27 is arranged inwardly of the cam surface 26a of the catch device 26, thereby firmly but yieldably supporting the door in the closed position. If desired separate catch members 26 may be employed on each door or for that matter, such catch devices may be employed at both upper and lower ends of the doors. In the drawing however, the second door 16a is secured in the closed position through the door 16 by suitable catch devices 28-28a on the door strips 19-19a.

In Fig. 5 of the drawing I have shown a somewhat modified construction wherein the door frame unit is adapted to extend less than the full height of the front of the cabinet. As shown in Fig. 5, the side and rear wall member 28 and the top wall member 29, correspond with the members 11 and 12 as shown in Figs. 1 to 3. The member 28 has front flanges or panels 28a which engage channels in the vertical frame rails 30, while the top transverse frame rail 31 is grooved to receive a protruding flange portion 29a of the top wall. The bottom transverse rail 31a is provided with a vertical groove 32 in the lower surface thereof to receive an upwardly extending panel or flange portion 33a on the bottom wall 33 of the cabinet. In other words, the door frame defined by the rails 30, 31 and 31a will extend from the top of the cabinet to a point somewhat above the bottom of the cabinet, and the front of the cabinet below the door opening will be permanently closed by the panel 33a. It will be apparent in this connection, that if it is desired to mount the shortened door frame inwardly of both ends of the cabinet, transverse rails of the type shown at 31a will be employed at both the top and bottom of the frame, and a top wall similar to the wall member 33-33a will be employed.

The rails 30, 31, 31a are secured together preferably in the interfitting manner previously described, to produce a rigid frame construction, and a pair of doors 34 are pivotally mounted in the frame by dowel pins 22a engaging recesses formed in the transverse rails 31-31a and in ends of the door reenforcing strips 35.

The showing in Fig. 5 is further intended to illustrate a more inexpensive construction wherein no transverse reenforcing strips are employed at the top and bottom of the door members. The adjacent vertical reenforcing strips 35a as well as the strips 35 are of simple L-shaped contour as seen in Fig. 6 of the drawing, and if desired an auxiliary strip 36 may be secured along one of the strips 35 to overlap and substantially seal clearance space between the adjacent strips 35a. Suitable stop strips 25a similar to the strips 25, are employed on inner surfaces of the transverse rails 31-31a to limit inward movement of the

doors and a spring catch member 37 similar to the member 26 is arranged on the lower surface of the rail 31 to resiliently engage the end of one or both of the door reenforcing strips 35a for supporting the doors in closed position.

The improved pivot mounting of the doors has been shown and described in connection with a unitary preassembled door frame unit, since in light weight cabinets the rigidity thereby insured 10 is of primary importance. It will be understood however, that the principles of the improved construction may be applied equally well to a cabinet construction wherein the transverse and vertical rails of the door frame comprise integral 15 parts of the detachably related sections of the cabinet. In such a cabinet, the doors would be separate from the other cabinet parts, and insertable in the door frame in the operation of assembling the same.

It will also be understood that the invention 20 is not limited to the particular form of pivot pin or dowel which has been shown in the drawing. An important feature of the construction is to provide a two-point suspension of each door 25 which is characterized by a degree of resistance to pivotal movement of the doors which insures firm support and smooth operation thereof in the continued use of the doors.

Having fully described my invention, what I 30 claim as new and desire to secure by Letters Patent is:

1. In a collapsible cabinet having a front door opening, a door frame unit comprising united and spaced vertical and transverse rails, said 35 rails bordering the door opening of said cabinet, a swinging door in said frame, cooperating means between the door and said transverse rails of the frame adjacent one of the vertical rails forming a two-point pivotal mounting of the door in said 40 frame, the end portions of the transverse rails projecting beyond said vertical rails, said pivot means comprising a pin and socket construction, and the pivot means of the door being arranged on projecting end portions of the transverse rails.

2. A collapsible cabinet of the class described 45 comprising detachably related top, bottom and unitary side and rear wall members, said members having flanges along front edges thereof, a separate door frame unit interfitting with said flanges, said door frame unit comprising pairs of vertical and transverse rails permanently secured together to form a rigid door frame, a pair of doors pivotally mounted in said frame, said transverse rails having end portions projecting beyond the vertical rails, and the pivot sides of 50 the doors and said end portions of the transverse rails having cooperating means forming the pivotal mounting of the doors in said door frame unit.

3. A collapsible cabinet of the class described 55 comprising detachably related top, bottom, and unitary side, front, and rear wall members, a separate door frame unit detachably coupled with the top, bottom, and front wall members, said unit comprising pairs of vertical and transverse rails secured together to form a rigid frame 60 unit, a pair of doors pivotally mounted in said unit, said transverse rails having end portions projecting beyond the vertical rails, the pivot sides of the doors and said end portions of the transverse rails having cooperating means forming the pivot mounting of the doors in said unit, said front wall portions extending from the vertical rails to the side walls of the cabinet, and the pivot sides of the doors having means bear- 65

ing upon said front wall portions when the doors are in closed position.

4. A collapsible cabinet of the class described comprising detachably related top, bottom, and unitary side, front and rear wall members, a separate door frame unit detachably coupled with the top, bottom, and front wall members, said unit comprising pairs of vertical and transverse rails secured together to form a rigid frame unit, a pair of doors pivotally mounted in said unit, said transverse rails having end portions projecting beyond the vertical rails, the pivot sides of the doors and said end portions of the transverse rails having cooperating means forming the pivot mounting of the doors in said unit, said front wall portions extending from the vertical rails to the side walls of the cabinet, the pivot sides of the doors having means bearing upon said front wall portions when the doors are in closed position, and said transverse rails intermediate the vertical rails having means extending into the door opening limiting closing movement of said doors.

5. In a collapsible cabinet of the class described having a front door opening bounded by vertically spaced transverse rails and inwardly extending front wall parts having finishing strips on the longitudinal edges thereof, the end portions of the transverse rails projecting beyond the door opening and said strips and extending onto the front wall parts, a door mounted between said transverse rail, and means at upper and lower ends of one side portion of the door and on projecting end portions of said rails for pivoting the door for swinging movement between said rails.

6. In a collapsible cabinet of the class described having a front door opening bounded by vertically spaced transverse rails and inwardly extending front wall parts having finishing strips on the longitudinal edges thereof, the end portions of the transverse rails projecting beyond the door opening and said strips and extending onto the front wall parts, a door mounted between said

transverse rails, means at upper and lower ends of one side portion of the door and on projecting end portions of said rails for pivoting the door for swinging movement between said rails, the pivot side portion of the door having a reinforcing strip extending the full length thereof, and said strip engaging the front wall part of the cabinet intermediate the free edge of said wall and the side portion of the cabinet.

10 7. In a collapsible cabinet of the class described having a front door opening bounded by vertically spaced transverse rails and inwardly extending front wall parts having finishing strips on the longitudinal edges thereof, the transverse rails having end portions projecting beyond the door opening and said strips and extending onto the front wall parts, a pair of door controlling said door opening, outer sides of the doors having reinforcing strips extending the full length thereof, means at the ends of said strips and on the projecting ends of said transverse rails for pivoting the doors for swinging movement in said rails, and the strips of said doors engaging the front wall parts outwardly of the free edges thereof when the doors are in closed position.

20 8. In a collapsible cabinet of the class described and having a front door opening bounded by vertically spaced transverse rails and inwardly extending front wall parts having finishing strips on the longitudinal edges thereof, the end portions of the transverse rails extending onto the front wall parts beyond the limits of the door opening and said strips, doors mounted between the transverse rails and collectively controlling the door opening, outer side edges of the doors overlying and engaging said front wall parts when the doors are in closed position, means hingedly coupling said outer edges of the doors to said transverse rails to provide swinging movement thereof into open and closed position, and said last named means being disposed on the projecting end portions of said rails beyond inner edges of said front wall parts.

HARRY DERMAN.
